J. E. LOVE

AUTOMATIC ANTENNA REGULATOR

Filed Dec. 12, 1925

Inventor:
Joseph E. Love,

by *Joseph E. Love*
His Attorney.

UNITED STATES PATENT OFFICE.

JOSEPH E. LOVE, OF SCHENECTADY, NEW YORK, ASSIGNOR TO GENERAL ELECTRIC COMPANY, A CORPORATION OF NEW YORK.

AUTOMATIC ANTENNA REGULATOR.

Application filed December 12, 1925. Serial No. 75,112.

My present invention relates to means for regulating the resonant wave length of an antenna system.

In the copending application of William W. Brown, Serial No. 78,202, filed December 29, 1925, there is disclosed an automatic antenna regulator comprising a pair of electric discharge devices adapted to control directly the energization of a magnetic amplifier. While the arrangement shown in the copending application, in general provides a very satisfactory form of regulator, I have found it desirable under certain conditions to control the excitation of the magnetic amplifier by means of a vibratory relay connected between the magnetic amplifier and the electric discharge devices.

In carrying my invention into effect I employ a magnetic amplifier to control the impedance, and therefore the tuning of the antenna circuit. A direct current generator having a separately excited, or a shunt field winding is employed to supply current to the regulating winding of the magnetic amplifier. Normally when the antenna circuit and the high frequency electromotive force supplied to the antenna are in tune, the controlling current supplied to the magnetic amplifier will maintain the magnetization of the amplifier constant. When there is any variation in the impedance of the antenna from normal, however, the energization of the field winding of the regulating generator will be either increased or decreased, depending on the nature of the change in the antenna, and thereby increase or decrease the current supply to the regulating winding of the amplifier. In this manner the magnetization of the amplifier is controlled and is increased or decreased, in accordance with the change in the impedance of the antenna to provide the proper correction in the impedance of the antenna circuit.

The novel features which I believe to be characteristic of my invention are set forth with particularity in the appended claims. My invention itself, however, both as to its organization and method of operation will best be understood by reference to the following specification taken in connection with the accompanying drawing in which the figure shows diagrammatically a circuit organization whereby my invention may be carried into effect. Referring to the

drawing, I have indicated at 1, a well known type of high frequency inductor alternator having a plurality of stationary armature windings 2 and a rotary field member 3, the latter being driven by a constant speed machine 4. Certain of the armature windings 2 are connected to the primary winding of a transformer 5, the secondary winding of which is connected in series relation with an antenna 6. Included in circuit with the antenna 6, are a variable impedance 7, by means of which initial adjustment of the antenna impedance may be made and a pair of primary transformer windings 8 and 9, which are inductively related to a pair of secondary transformer windings 10 and 11 respectively.

A saturated core regulator or magnetic amplifier 12 is employed to control the impedance of the antenna circuit. The regulator may be of the type disclosed in Letters Patent of the United States to James C. Armor, No. 1,219,215, while the particular form of the controller which may be used may be of the type described in Letters Patent of the United States to Ernst F. W. Alexanderson, No. 1,328,797.

In the present instance, the saturated core regulator comprises the usual high frequency windings 13, connected through condensers 14 and 15 to the secondary winding 16 of an air core transformer 17, and a regulating winding 18. The primary winding 19 of the transformer 17 is connected in series relation with the antenna 6. The regulating winding 18 of the magnetic amplifier is supplied with direct current from a generator 20 through an adjustable resistance unit 21. The amount of current supplied to winding 18 is controlled by varying the separately excited field winding 22 of the generator 20. Variation in the field excitation is obtained by controlling a plurality of resistors, one of which, 23, is connected in shunt with the field winding 22, while the other 24 is connected in series with field winding 22.

The resistors 23 and 24 are controlled by a vibratory relay 25 in such a manner that the current flowing in the field winding 22 is alternately increased above a certain amount and decreased a corresponding amount during equal periods of time so that the resultant field magnetization of the generator is maintained substantially constant during

normal operation. Consequently, the current flowing in the controlling winding 18 is substantially constant, so that the impedance of the circuit including winding 16 remains constant, and no variation is produced in the impedance of the antenna circuit that is due to the action of the magnetic amplifier.

In order to control the resistors 23 and 24 so as to automatically provide correction in the antenna circuit for variations of the antenna impedance from normal, I employ a plurality of electric discharge devices which govern the action of a vibratory relay 25.

Relay 25 comprises a bent permanent magnet 26, carrying at one end a vibratory arm 27 which is adapted to cooperate with a pair of polarized members 28 and 29 of like polarity, and a pair of contacts 30 and 31, the latter contacts being adapted to control the operation of the resistors. Polarized member 28 is mounted on a core member which carries a pair of windings, one of which, 32, may be energized from a 60 cycle source of power indicated at 33, while the other winding 34 is included in circuit with an electric discharge device 35. Polarized member 29 is mounted on a core member which carries a pair of windings 36 and 37, similar to windings 32 and 34. Windings 36 and 32, however, are wound to produce opposite polarities with respect to one another. Winding 37 is connected in circuit with a second electric discharge device 38. The vibratory arm 27 is connected by a wire 39 to one side of the field winding 22. Contact 30 is connected to a point on resistor 23, and contact 28 is connected to a point on the series resistor 24. When arm 27 is in central position current to the field winding 22 will flow through a portion of resistor 24 to give a normal excitation to field winding 22. When arm 27 is in engagement with contact 31 the field winding 22 will be connected in shunt with a circuit which will include wire 39, arm 27, contact 31 and a portion of resistor 23, so that the voltage and current supplied by generator 21 to the magnetic amplifier will be reduced below normal. When arm 27, on the other hand, is in engagement with contact 30 the greater portion of the series resistor 24 will be short circuited and the current through field winding 22 will be increased above normal. The variations in current in winding 22 above and below normal, which are produced in this manner, will be adjusted equal.

When 60 cycle current is supplied to coils 32 and 36 of relay 25, arm 27 will vibrate at 60 cycles, the arm remaining in engagement with contact 30 and 31 for equal periods of time and, therefore, controlling the energization of winding 22 in such a way as to alternately increase and decrease the magnetization produced by winding 22.

To control operation of the vibratory arm 27 in accordance with variations in the an-

tenna impedance, I employ a pair of electric discharge devices 35 and 38, each comprising the usual anode, cathode and grid. The anodes or plate members of the two discharge devices are connected to the secondary 70 transformer windings 10 and 11 in such a way that the electromotive force supplied to the two anodes will be in phase with each other. The plate circuit of each discharge device is completed through one of the windings 34 or 37. The grid elements of the discharge devices are connected to one of the armature windings of the inductor alternator

1. A resistor 40 and condensers 41 and 42 are connected in circuit with the armature winding of the alternator so that the phase relation of the electromotive forces supplied to the two grids may be adjusted relatively to one another and relatively to the plate electromotive force as desired. Normally, with 80 the antenna in tune with the electromotive force of the alternator 1, the electromotive force supplied to the plate member of each discharge device 35 and 38 may differ in phase from the electromotive force supplied to the associated grid member by an amount less than 90°, and the difference in phase between the plate and grid electromotive forces of the two discharge devices may be equal. As thus arranged, if the antenna is in tune 85 with the high frequency electromotive force of the alternator 1, equal amounts of current will be supplied from the discharge devices 35 and 38 to coils 34 and 37. Energization of coils 34 and 37, however, will not affect the 100 operation of the vibratory arm 27 as long as the coils 34 and 37 are supplied with current for equal periods of time. When the impedance of the antenna varies from normal, the phase relation of the electromotive forces 105 supplied to the grids and plates of the discharge devices will vary, and as a result the current supplied in any one cycle, from one discharge device will flow for a longer period of time than from the other discharge device. 110 This will cause one of the relay coils 34 or 37, as the case may be, to be supplied with current impulses of longer duration than those supplied to the other relay, and as a 115 result vibratory arm 27 will lag for a longer time at the pole pieces 28 or 29 which is supplied with the greater amount of current.

If the impedance of the antenna has, for example, decreased below normal, coil 37 will be energized for a longer period and at a 120 higher value than coil 34. Arm 27 will, therefore, lag longer at polepiece 29 than at 28 thus including a portion of resistor 23 in shunt to field winding 22 for a longer period of time than in normal operation. The 125 total current supplied to field winding 22 and amplifier winding 18 in a given period will therefore be reduced from normal, causing an increase in the impedance of the circuit including winding 16, and a corresponding in- 130

crease in the impedance of the antenna circuit which will thereby restore the impedance of the antenna to normal.

A pair of condensers 43 and 44 is associated with the discharge devices 35 and 38 and tend to smooth out the direct current impulses supplied to coils 34 and 37. These condensers also may act as a by-pass for radio frequency currents. While I have shown a 60 cycle circuit in connection with relay 25, obviously any frequency desired may be employed.

What I claim as new and desire to secure by Letters Patent of the United States, is,—

1. In combination, an antenna, a saturated core regulator associated with the antenna, said regulator including a regulating winding, a source of direct current connected to said winding, and means controlled by variations in the impedance of the antenna, for varying the current supplied from said source to said regulating winding.

2. In combination, an antenna, a saturated core regulator associated with the antenna, said regulator including a regulating winding, a source of direct current connected to said winding and means controlled by variations in the impedance of the antenna for varying the current supplied from said source to said regulating winding, said means including an electric discharge device.

3. In combination, an antenna, a saturated core regulator associated with the antenna, said regulator including a regulating winding, a source of direct current connected to said winding, means controlled by variations in the impedance of the antenna for varying the current supplied from said source to said regulating winding, said means including an electric discharge device, and a relay controlled by said discharge device.

4. In combination, an antenna, a saturated core regulator associated with the antenna, means including a generator for varying the excitation of the regulator, a field winding associated with the generator, a plurality of resistors connected in circuit with the field winding, and means controlled by variations in the impedance of the antenna for controlling the operation of the resistors.

5. In combination, an antenna, a saturated core regulator associated with the antenna, means including a generator for varying the excitation of the regulator, a field winding associated with the generator, a plurality of resistors connected in circuit with the field winding and means for controlling the opera-

tion of the resistors, said means including an electric discharge device controlled by variations in the impedance of the antenna.

6. In combination, an antenna, a saturated core regulator associated with the antenna, means including a generator for varying the excitation of the regulator, a field winding associated with the generator, a plurality of resistors connected in circuit with the field winding, and means controlled by variations in the impedance of the antenna for controlling the operation of the resistors, said means including an electric discharge device, and a normally vibratory relay controlled by said device.

7. In combination, an antenna, a saturated core regulator associated with the antenna, means including a normally vibratory relay for controlling the excitation of the regulator, and means including an electric discharge device for modifying the operation of the relay.

8. In combination, an antenna, a saturated core regulator associated with the antenna, means including a normally vibratory relay for controlling the excitation of the regulator, said relay including a plurality of oppositely related windings, and means including a plurality of discharge devices for controlling the energization of said windings to affect the vibration of said relay.

9. In combination, an antenna, a magnetic amplifier associated with the antenna, a source of current connected to the regulating winding, means including a vibratory relay for controlling the current supplied to the regulating winding, said relay having a plurality of windings energized from a source of electromotive force having a relatively low frequency, and a plurality of windings controlled by variations in the impedance of the antenna.

10. In combination, an antenna, a magnetic amplifier associated with the antenna, means including a generator for varying the excitation of the amplifier, a field winding associated with the generator, a plurality of resistors associated with the field winding, a vibratory relay for governing the operation of said resistors and means controlled by variations in the impedance of the antenna for controlling the operation of the relay, said means including a plurality of electric discharge devices.

In witness whereof I have hereunto set my hand this 11th day of December, 1925.

JOSEPH E. LOVE.
